Attest.

UNITED STATES PATENT OFFICE.

FRANK W. MEYER, OF OSHKOSH, WISCONSIN, ASSIGNOR TO THE OSHKOSH TRUNK COMPANY, OF OSHKOSH, WISCONSIN, A CORPORATION OF WISCONSIN.

COMBINED HAT AND SHOE DRAWER.

Application filed December 29, 1924. Serial No. 758,492.

This invention relates to a combined hat and shoe drawer for wardrobe trunks.

The object of the invention is to offset the hat compartments so that two men's hats may be carried in a drawer space which in itself is not long enough to accommodate two hats if arranged side by side.

The invention consists further in the matters hereinafter described and claimed.

10 In the accompanying drawings—

Fig. 1 is a view looking into an open wardrobe trunk and showing a tier of drawers in the drawer section, the bottom most drawer embodying the features of my invention;

15 Fig. 2 is a top plan view on an enlarged scale of the bottom drawer to show the offset hat compartments; and

Fig. 3 is a vertical sectional view taken 20 on the indirect line 3—3 of Fig. 2.

The wardrobe trunk shown in Fig. 1 is of the center opening type and has two vertically hinged together sections 1 and 2, the former being the wardrobe section and the 25 latter the drawer section. In the section 2 is a tier of drawers, the lowermost one 3 embodying my invention.

The drawer 3 is divided by vertical partitions to have two hat compartments 4, 5 30 and two pairs of shoe pockets or compartments 6, 6 and 7, 7. The hat compartments 4, 5 take in opposite corners of the drawer, and each has a width less than the width of the drawer. The partition of one compartment extends into the other compartment at their contiguous corners, and this offsets the compartments and allows each to have a length greater than half the length 35 of the drawer so that the drawer may carry two men's hats 8, 9 in a length which is not sufficient to carry these two hats if placed side by side.

The hat compartment 4 is formed in part 40 by the front wall 10 of the drawer and its end wall 11. The remaining portion of the compartment 4 is formed by a right-angle partition wall having one section 12 parallel to the front wall and with its side edge in a groove or channel on the inside of the 45 end wall 11. The other section 13 of this partition is parallel to the end wall 11 and extends to the front wall 10 where its side edge is received in a groove or channel, as 50 shown in Fig. 2.

55 The other hat compartment 5 is formed in

part by the rear wall 14 of the drawer and the other end wall 15. The front part of this compartment is formed by a partition wall 16 parallel to the rear wall 14 and extending between the end wall 15 and the partition 13 of the other compartment. The side edges of the partition 16 are in grooves or channels in the partition 13 and end wall 15, respectively, as shown in Fig. 2. The remainder of the compartment 5 is formed by 60 a partition wall 17 parallel to the end walls of the drawer and extending between the partition 12 and the rear wall 14 with its side edges in grooves or channels in said walls. 70

It will be noted that by this arrangement the right-angle corner of the partition 12—13 extends into the compartment 5 clear of the hat 9 therein. Having the compartments 4 and 5 overlapping in this manner 75 enables both compartments, each longer than half the length of the drawer, to be arranged within the length of the drawer.

In each compartment 4, 5 there is a slide 18 having a center opening 19 of a size to 80 receive a man's hat. The slide 18 carries a flange 20 about the opening and which flange extends to one side of the slide, as shown in Figs. 2 and 3. The outer edge of this flange is shaped to fit the brim of the 85 hat, and when the slide is in its compartment the flange extends toward the adjacent wall of the drawer so as to hold the brim of the hat close to the drawer wall and hold the hat from displacement. 90

As shown in Fig. 2, the slides 18 extend the full lengths of their respective compartments. The slide in compartment 4 extends between the end wall 11 and partition wall 13 with its side edges in grooves in said 95 walls. The slide 18 in compartment 5 extends past the right-angled corner of partition 12—13 and has its side edges in grooves in end wall 15 and partition wall 17. Beginning in grooves, the slides may be slid in and out of the drawer for putting a hat in and removing it from the drawer. 100

The compartments 6 and 7 are formed by dividing the drawer space left by the hat compartments into halves, as by partitions 105 21, 22, respectively, with their side edges in grooves, as shown. With all the partitions in grooves, the full drawer space may be used when desired by removing the partitions. 110

I claim as my invention:

1. A single drawer or compartment for trunks divided by vertical partitions into two offset hat compartments, each of a width less than the width of the drawer and formed in part by the associated walls thereof, the partition of one compartment extending into the other compartment at their contiguous corners so that each compartment may have a length greater than half the length of the drawer taken up by said compartments, and vertical hat carrying slides in said compartments with the slides extending the full length of their respective compartments.
2. A single drawer for trunks divided by vertical partitions into two hat compartments taking in opposite corners of the drawer and each compartment having a width less than the width of the drawer and formed in part by the associated walls thereof, the partition for one compartment extending into the other compartment at their contiguous corners so that each compartment may have a length greater than half the length of the drawer, vertical hat carrying slides, one in each compartment and extending the full length thereof, each slide having a band around its opening to fit against the

brim of the hat, said slides being arranged adjacent their respective drawer walls with their bands extending toward the same for holding the hat brims at said walls.

3. A single drawer for trunks having a right-angled partition therein, said partition having two sections, one shorter than the width of the drawer and extending to one of the side walls thereof, the other section being longer than half the length of the drawer but shorter than the full length thereof and extending to one of the end walls of the drawer, a second partition outside of the first partition adjacent the right-angled corner thereof and extending between the longest section of said first partition and the side wall of the drawer not engaged by the short section, and hat carrying slides both extending lengthwise of the drawer, one slide engaging the short section of the first partition and the end wall of the drawer engaged by said partition, and the other engaging the second partition and the other end wall of the drawer.

In testimony that I claim the foregoing as my invention, I affix my signature, this 23rd day of December, 1924.

FRANK W. MEYER.
